BENNSELAER J. SMITH, OF SOUTH BETHLEHEM, NEW YORK, ASSIGNOR TO THE BATES-LITE CO., COMPOSED OF MILDRED A. SMITH AND CHARLES Z. SMITH, BOTH OF ALBANY, NEW YORK.

FLASH LIGHT.

Application filed June 5, 1926. Serial No. 113,985.

This invention relates to electric flash-lights of the same general type which are now used with dry cell batteries, but which employ a generating means for their source 5 of energy in lieu of the batteries whereby the expense and inconvenience of the replacement of the batteries are eliminated.

The invention primarily comprehends a flash-light including a generator preferably 10 operable by a spring motor and contemplates further, manually operable means for controlling the speed of the generator within defined limits for the purpose of increasing or decreasing the intensity of the light in 15 accordance with the use to which the same is to be put, whereby the operator may conserve the power of the spring motor to prevent undue winding thereof; to increase the length of life of the lamp filament, and generally to eliminate unnecessary wear on the 20 working parts.

The invention furthermore aims to provide a flash-light of the character set forth in which the generator may be started with 25 no load, thereby insuring a more rapid generation of a maximum current and precluding a failure of the generator to operate when the tension of the spring motor is materially reduced.

30 The invention furthermore contemplates in a flash-light generator of the character specified, an automatic keeper means for the permanent magnets which functions to prevent undue loss of their magnetism, and 35 which keeper at the same time serves to prevent accidental operation of the generator when the same is not in actual use.

As a still further object the invention provides means for facilitating the focusing of 40 the lamp with respect to a fixed reflector whereby an intense restricted beam or a subdued diffused beam may be produced at the will of the operator.

As a further object the invention comprehends a common manually operated means 45 adapted upon various shifting movements to start or stop the spring motor, control the speed of the generator, and focus the lamp.

The invention furthermore resides in the 50 provision of a flash-light as heretofore set forth, which is comparatively simple in its construction and mode of operation, which

may be produced on an economical basis, and which is highly efficient in its purpose.

With the above recited and other objects 55 in view, reference is had to the following specification and accompanying drawings in which there is exhibited one example or embodiment of the invention which is in no way intended as a limitation upon the scope 60 of the appended claims as it is to be clearly understood that variations and modifications which properly fall within the scope of said claims may be resorted to when found expedient.

In the drawings—

Figure 1 is a longitudinal sectional view through a flash-light constructed in accordance with the invention;

Figs. 2, 3, 4, 5 and 6 are transverse sectional views taken approximately on the lines 2—2, 3—3, 4—4, 5—5 and 6—6 of Fig. 1, and looking, respectively, in the directions indicated by the arrows;

Fig. 7 is a fragmentary longitudinal sectional view taken approximately on the line 7—7 of Fig. 6, indicating the normal inactive position of the operating parts;

Fig. 8 is a similar view taken approximately on the line 8—8 of Fig. 6, illustrating 80 the active position of the parts;

Fig. 9 is a detail edge view of the main bearing wall of the train of gearing and the rotor or armature shaft.

Referring to the drawings by characters 85 of reference, the flash-light includes a suitable casing 10 which is preferably of cylindrical formation and having threaded engaged on its forward end a ring 11 which serves to clamp the reflector 12 and lens 13 90 in properly related position to each other and to the forward end of the casing. The rear end 14 of the casing is of a reduced diameter and snugly receives the substantially cup-shaped rear casing section 15.

The main body 10 of the casing substantially at its juncture with the reduced rear end 14, is provided with a transverse wall 16, which is secured in place in any suitable manner, such as by screws 17 threaded into 100 rearwardly bent ears 18. The wall 16 has secured centrally thereof and projecting rearwardly therefrom, a tubular bearing trunnion 19 upon which the forward end of

a hollow shaft 20 is rotatably mounted. The shaft has keyed thereto a ratchet wheel 21 and the shaft and ratchet are held against rearward accidental movement and displacement from the bearing trunnion by a transverse bar 22 secured in spaced relation to the bearing wall by the fastening elements or screws 17 which thread into forwardly bent ears 23. The transverse bar 22 is provided 10 with a central aperture 24 of a diameter to snugly receive the hollow shaft 20, while the boss or hub 25 of the ratchet wheel abuts said bar and is rotatably retained between the forward face of the bar and the rear 15 face of the wall 16. At its rear end the shaft 20 has secured therein a stud 26 formed with a reduced rearwardly extending portion 27 which is engaged in the centrally threaded aperture of a reinforcing spider 28 20 riveted or otherwise secured to the end wall 29 of the cup-shaped rear casing so that the said rear casing section is connected to the shaft 20 and upon rotation in a clockwise direction, functions to turn the shaft 20 and 25 ratchet wheel 21 therewith. It is also obvious that turning movement in an anti-clockwise direction will effect unthreading and detachment of the casing section 15 from the shaft when it is desired to gain access 30 to the interior of the rear portion of the flash-light.

Mounted on the hollow shaft in axially aligned relation are a pair of spring sleeves 30 and 31, the former being secured at its 35 rear end by a key 32 which also serves to secure the stud 26 to said hollow shaft. A spring barrel 33 is loosely mounted on the spring sleeve 30 with its forward end wall 34 secured to the rear end of the spring 40 sleeve 31. A spiral or helical spring 35 has its inner end 36 attached to the spring sleeve 30 and its outer end 37 attached to the spring barrel 33, the convolutions of the spring being so disposed that turning movement of the rear casing section 15 in a clockwise direction will effect a winding of the spring. A second spring barrel 38 is loosely mounted on the spring sleeve 31 and its forward wall 39 is in the form of an internal 45 or ring gear. A second helical or coil spring 40 is arranged within the second spring barrel 38 and has its inner end secured to the spring sleeve 31 and its outer end secured to the outer wall of the said 50 spring barrel similar to the arrangement of the first-mentioned spring, so that it is obvious that the two spring units are coupled in gang formation whereby clockwise turning movement of the rear casing section 15 will effect winding of both of said springs.

The ratchet 21 is engaged by a pawl 41 mounted on and pivoted at 42 to the rear face of the partition wall 16, a spring 43 serving to normally effect engagement of the 55 pawl with the ratchet wheel 21 so as to lock

the hollow shaft 20, the rear casing section 15, and the spring sleeve 30 against retrograde turning movement and allowing the springs when wound up to produce a driving tension on the internal or ring gear 39. A pinion 44 70 meshes with the internal or ring gear 39 and is carried by a shaft 45, which extends through and has bearing in the transverse bar 22, the partition wall 16 and the rear wall 46 of a generator housing 47, which rear wall is spaced forwardly from the partition wall 16 to define a compartment within which a suitable train of gears is arranged for increasing the speed of the generator 75 rotor shaft 48, which generator rotor shaft 80 is formed with a reduced bearing terminal 49 journaled in the bore of the tubular bearing trunnion 19.

The generator includes a rotor 50 secured to the rotor shaft 48 arranged within the 85 rotor casing 47, and made up of laminations. The rotor is of the six-pole armature type in the embodiment illustrated, and constitutes a permanent magnet, which is designed to rotate at a high rate of speed, and the 90 field which consists of six generator coils 51 wound in series about the six laminated cores 52. One terminal 53 of the wire which constitutes the generator coils is connected to an insulated contact arm 54 which is secured to the generator housing and insulated therefrom so that the free end of the contact arm is disposed adjacent the inner periphery of the casing 10. The other terminal 55 of the wire which constitutes the 95 generator coils leads to and connects with the insulated central contact element 56 of a lamp socket 57 in which a lamp 58 is mounted. The lamp socket is attached to a pair of stub shafts 59 which project rearwardly through apertures in the substantially frusto-conical forwardly projection portion 60 of the generator housing so that the lamp socket and lamp are mounted for axial movement with respect to the fixed reflector 12 for focusing the lamp in accordance with the manner in which it is to be used.

In order to govern the speed of rotation of the generator rotor, a centrifugal governor is employed which consists of a pair of spring arms 61 attached to the rotor shaft at their inner ends and having weights 62 secured to their free ends with fiber or other suitable terminal pieces 63 projecting beyond the weights and spring arm terminals. In order to provide means for regulating the radial expansion of the weighted governor arms, a drum-like member 64 is provided and is mounted for axial sliding movement with respect to the governor arms on a bearing stud 65 which is secured to the forward portion 58 of the generator casing and extends rearwardly toward the rotor shaft 110 where it is formed with a central bearing 115 120 125 130

bore 66 in which the forward end of the rotor shaft is mounted. The drum-like member 64 is provided with a frusto-conical forward portion 67 which presents gradually increasing internal diameters toward the rear end so that upon forward movement the terminal pieces engaging therewith are permitted to expand to a greater degree for increasing the speed of rotation of the rotor. 10 Conversely, rearward movement of the member 64 reduces the radial expansion of the governor arms to reduce the speed of rotation of the rotor. In order to provide means for shifting the member 64 forwardly or rearwardly, a shifting fork 68 is provided which is fulcrumed in a bearing member 69, the terminals of the fork engaging in the hooked lugs 70 on the forward end of the member 64. The shifting fork is provided 20 with an outwardly projecting arm 71 having a manipulating handle 72 disposed exteriorly of the casing 10 and said arm extends through a plate 73 slidable on the inner face of the casing adjacent the slot 74 through which the arm 71 projects. The plate is provided with a depending contact finger 75 in the path of movement of which the contact arm 54 is disposed so that after an initial swinging movement of the arm 30 71, the contact finger 75 will engage the arm 54 to close the circuit to the lamp. In order to maintain the plate 73 against the inner periphery of the casing 10 tightly so that the arm 71 will remain in any position that it is placed, a coiled expansion spring 76 is 35 interposed between the bearing stud and the inner face of the plate.

The member 64 in addition to serving as a governor regulating device, also locks the 40 rotor shaft and spring motor against turning movement by the frictional engagement with and braking action against the forward side of the rotor 50. The member 64 also serves as a magnetic keeper means 45 for the permanent magnets of the rotor for preventing undue loss of magnetism, and, at the same time, due to the fact that it is magnetically attracted by the rotor, functions to prevent accidental movement of the 50 same rearwardly to its active position.

In order that the handle 72 may further serve in the capacity of a means for axially shifting the lamp socket and lamp to regulate the focus of the flash-light, the stub shafts 59 are provided with reduced rear ends 77 extending through apertures in the member 64 and define, at the juncture of said reduced ends 77 with the stub shafts, shoulders 78 with which the member 64 engages after a predetermined amount of movement, to slide the stub shafts 59 and the socket and lamp axially forward. Coiled expansion springs 79 are connected with the stub shafts adjacent the shoulders 78 and the opposite ends bear against the inner

surface of the forwardly projecting portion 60 of the generator housing so that the socket and lamp are moved by the pins rearwardly until the lamp socket engages the end of the portion 60 of said housing. 70

In order to provide means for lubricating the bearings of the gear train, oil-soaked strips of material 80 are arranged in channel-like plates 81 held on the forward face of the generator casing rear wall and the 75 rear face of the partition wall 16, respectively.

In order to facilitate turning movement of the rear casing section 15, a hexagonal or multi-faced cap 82 is detachably associated 80 with the rear end of said casing section 15 by a bayonet joint 83, which also prevents rolling of the lamp when laid on a flat surface. The cap, is also formed with a bulged portion 84 defining together with the wall 85 29, a space for the reception of an extra lamp.

In use, the operator initially moves the manipulating handle 72 rearwardly so that the member 64 is disengaged from the rotor, permitting the spring motor to function for driving the rotor shaft, which starts and attains a considerable momentum, thereby generating a source of energy without any load on the generator. A continued rearward 90 movement brings the contact finger 75 into engagement with the contact arm 54, thereby closing the circuit to the lamp. Continued rearward movement of the manipulating handle 72 moves the member 64 axially forward thereby allowing, due to the frusto-conical formation of the forward portion, the governor arms to expand for increasing the speed of the rotor between the limits illustrated. A still further movement of the handle 72 rearwardly causes the member 64 to engage the shoulders 78 of the stub shafts 59, thereby effecting axial adjustment of the lamp socket and lamp to 100 vary the focus. The manipulating handle 110 may be set at any position depending on what the operator desires to use the light for.

What is claimed is:

1. A flash-light, including an electric lamp, 115 a fixed reflector, a generator connected with said lamp for producing a source of energy to illuminate the same, a spring motor for driving the generator, a governor for regulating the speed of operation of the generator, and including a common means for controlling the governor and effecting relative movement of the lamp with respect to the fixed reflector to vary the focus of the same. 120

2. A flash-light, including an electric lamp, a fixed reflector, a generator for producing a source of energy to illuminate the lamp, a spring motor for driving the generator, a governor for regulating the speed of operation of the generator, and including 125 130

4

a common manipulating operable means for respectively connecting and disconnecting the lamp with the generator, for starting and stopping the motor, for controlling the governor speed, and for effecting relative movements of the lamp with respect to the reflector for varying the focus.

- 5 3. In a flash-light, a generator including a stator and a rotor, a spring motor for driving the rotor, a centrifugal speed governor connected with the rotor, and including a combined device constituting a brake engageable with and disengageable from the rotor to hold the same respectively inactive 10 and allow for driving of the rotor, to serve as a governor regulator to permit of variation of the speed of the rotor and to constitute a magnetically attracted keeper for the rotor to prevent loss of magnetism.
- 15 20 4. In a flash-light, a generator including a stator and a rotor, a spring motor for driving the rotor, a centrifugal speed governor connected with the rotor, and including a combined device constituting a brake engageable with and disengageable from the rotor to hold the same respectively inactive 25 and allow for driving of the rotor, to serve as a governor regulator to permit of variation of the speed of the rotor and to con-

stitute a magnetically attracted keeper for 30 the rotor to prevent loss of magnetism, said flash-light including a lamp, a fixed reflector, a switch, and a circuit including the lamp, switch and generator, and a common manipulating means operable to move said device, open and close the switch, and adjust the lamp with respect to the reflector for varying the focus.

35 5. A flash-light including a casing having a fixed reflector, a lamp, a lamp socket therefor mounted for relative movement with respect to the reflector, a circuit including a spring-motor-operated generator, the said lamp socket and a switch, means for normally holding the lamp socket in one position 40 with respect to the reflector, a common means for controlling the opening and closing of the switch and for effecting movement of the lamp socket with respect to the reflector for focusing the lamp; in combination with 45 a centrifugal speed governor connected with the rotor of the generator, and including a movable magnetic brake operable by the common switch-closing and lamp-focusing means, said brake having a governor-engaging portion for varying the speed of the 50 governor upon movement of the brake.
